M. H. JENKINS

FOUNTAIN BRUSH

Filed Nov. 2, 1925

Inventor:

Mark H. Jenkins,

834

F. G. Fischer,

Witness:

Fred G. Fischer.

Attorney:

Patented July 13, 1926.

UNITED STATES PATENT OFFICE.

MARK H. JENKINS, OF KANSAS CITY, MISSOURI.

FOUNTAIN BRUSH.

Application filed November 2, 1925. Serial No. 66,311.

My invention relates to paint brushes and embodies a hollow brush to which the paint is automatically fed under pressure from a source of supply and discharged in the form 5 of spray, the brush serving as a means for confining the spray to the surface to be painted and for spreading the paint uniformly over said surface, so that there will be no waste of paint or damage to adjacent 10 surfaces by reason of a portion of the paint dripping, or splashing thereon.

In order that the invention may be fully understood, reference will now be had to the accompanying drawing, in which:

15 Fig. 1 is a vertical central section of the brush.

Fig. 2 is a plan view of the brush.

Fig. 3 is an inverted plan view of the brush.

20 Referring now in detail to the various parts, 2 designates an open member of any desirable configuration, it being preferably in the form of an annulus as shown more clearly by Fig. 2.

25 4 designates paint applying means preferably in the form of bristles, the upper ends of which are secured in holes 6 in the annulus 2, their lower ends spreading out to form a circular inclosure as best shown by 30 Fig. 3.

35 8 designates a conical shield secured at its enlarged end to the annulus 2 in any suitable manner, bolts 10 being shown for that purpose. The reduced end of the shield 40 8 has a neck 12 in which a tube 14 is removably secured.

45 In the present instance the tube 14 is in two sections 16 and 18 connected by a coupling 20. The section 18 extends through the neck 12 and is provided near its lower end with a peripheral flange 22, which is drawn against the interior of the conical shield 8 as the coupling 20 is screwed against the outer end of the neck 12, thereby firmly 50 clamping the section 18 in place. The inner end of the section 18 is threaded and provided with a removable nozzle 24 having a discharge orifice 26. A suitable gasket 28 is interposed between the flange 22 and the nozzle 24 to provide a leak proof joint.

When a wall or other surface is to be coated with paint, varnish, stain, or other fluid, the outer end of the tube 14 is connected to a suitable source of supply from which the fluid is forced through the tube 55 14 and discharges from the nozzle 24 in the form of spray. As the brush is held with its bristles against the surface the discharged spray is prevented from splashing or running down such surface, or onto adjacent 60 surfaces such as a floor, furniture, etc., but is confined to the area enclosed by the circular row of bristles 4. By moving the brush in the usual way over the surface the same can be coated in a uniform manner in 65 much less time than is required with an ordinary brush which must be dipped by the workman at intervals into a pot containing the coating liquid.

Should the tube 14 or the nozzle 24 become clogged they can be easily cleaned after unscrewing the coupling 20 and removing said tube 14 from the shield 8.

It is obvious that liquids other than paint, varnish, etc., can be applied with the brush, 75 and while I have shown and described the preferred form of said brush, I reserve the right to such modifications thereof as properly fall within the spirit and scope of the invention as claimed.

Having thus described my invention, what I claim and desire to secure by Letters Patent, is:

1. A brush consisting of an annulus, bristles secured to said annulus, a conical shield 85 having its large end connected to the annulus, and a tube secured in the small end of said shield.

2. A brush consisting of an annulus, bristles secured to said annulus, a conical shield 90 having its large end connected to the annulus, a tube extending into the small end of said shield, means for clamping said tube and the shield together, and a spray nozzle 95 on the inner end of said tube.

In testimony whereof I affix my signature.

M. H. JENKINS.
